DISPLAY STAND FOR JARS OR THE LIKE

Richard C. Kearns, Jackson Heights, and Alvin Eisenberg, Little Neck, N.Y., assignors to Q-Tv Inc., New York, N.Y., a corporation of New York

Filed Jan. 22, 1966, Ser. No. 739

Term of patent 14 years

(Cl. D80—9)

We claim:

The ornamental design for a display stand for jars or the like, substantially as shown and described.
